(57) **CLAIM**

The ornamental design for a nitrous oxide flow solenoid bracket, as shown and described.

DESCRIPTION

FIG. 1 is a perspective view of a nitrous oxide flow solenoid bracket, showing my new design;

FIG. 2 is a right side elevational view;

FIG. 3 is a left side elevational view;

FIG. 4 is bottom plan view;

FIG. 5 is an inverted back side elevational view;

FIG. 6 is a top plan view; and,

FIG. 7 is a front side elevational view.
